UNITED STATES PATENT OFFICE.

PATRICK HOLMSTROM, OF HANCOCK, MINNESOTA, ASSIGNOR OF ONE-HALF
TO WILLIAM RAMSEY CRAIG, OF ST. PAUL, MINNESOTA.

WAGON-POLE CAP.

SPECIFICATION forming part of Letters Patent No. 706,754, dated August 12, 1902.

Application filed May 1, 1902. Serial No. 105,502. (No model.)

To all whom it may concern:

Be it known that I, PATRICK HOLMSTROM, a citizen of the United States of America, residing at Hancock, in the county of Stevens 5 and State of Minnesota, have invented certain new and useful Improvements in Wagon-Pole Caps, of which the following is a specification, reference being had therein to the accompanying drawings.

10 My invention relates to certain new and useful improvements in wagon-pole caps, and has for its object a cap of a novel form hung on the end of the pole, which shall embrace a means for preventing the neck-yoke ring 15 from becoming disengaged from the pole.

My invention has for its further object a device of this character which shall be of simple and economical construction, as well as being efficient in operation.

20 With the above and other objects in view the invention further resides in the novel details of construction and combination of parts to be clearly described in the following specification and then set forth in the claim.

25 Referring to the accompanying drawings, forming a part of this application, and wherein like characters of reference indicate similar parts throughout the several views, Figures 1, 2, 3, and 4 illustrate a side, top, bottom, 30 and end view of the device; and Figs. 5 and 6 illustrate details of the tongue or clip.

The pole 1 receives upon its outer end the sleeve 2, secured in any suitable manner. At its forward end this sleeve is closed and 35 carries a pair of spaced lugs 3, formed integral with the said end of the sleeve and located between the top and the bottom thereof. Along its under face the sleeve carries an integral fin 4, of less width than the sleeve 40 and extending from a point approaching the

inner end of the sleeve downwardly at an angle to the sleeve, being widest at a point in proximity to the other end of the sleeve, from whence it merges out and upwardly, as at 5, to form a hook 6, having an L-shaped seat 45 formed on its inner upper edge, as at 7. Between the said spaced lugs a tongue or clip 8 is pivoted at its head 12 by means of the rivet or the like, the tongue having an inward movement, which is limited by the 50 sleeve 2, and has its free end engaging in said L-shaped seat. A spring 10 is secured to the tongue, as at 11, extends over the head of the tongue and between the lugs, and has its free end bearing against the end of sleeve 2. 55

Having thus fully described my invention, what I claim as new, and desire to secure by Letters Patent, is—

The combination with a wagon-pole, of a sleeve on the end thereof carrying a fin on 60 its under side extending downwardly at an angle to the sleeve and terminating in an arc-shaped hook having an L-shaped seat on its inner upper edge, a pair of spaced lugs formed integral with the end of the sleeve between 65 the top and bottom thereof, a tongue pivotally secured between said lugs and having its free end engaging in said seat on the hook, the inward movement of the tongue being limited by the outer end of the sleeve, and a 70 spring secured to the tongue engaging over the head thereof and having its free end engaging between said lugs and the end of the sleeve, substantially as described.

In testimony whereof I affix my signature 75 in the presence of two witnesses.

PATRICK HOLMSTROM.
